UNITED STATES PATENT OFFICE

161,623

DOILY OR THE LIKE

Kenneth C. Hamilton, Milwaukee, Wis., assignor to Milwaukee Lace Paper Company, Milwaukee,
Wis., a corporation of Wisconsin

Application March 6, 1950, Serial No. 8,353

Term of patent 14 years

(Cl. D59—2)

To all whom it may concern:

Be it known that I, Kenneth C. Hamilton, a citizen of the United States, residing at Milwaukee, in the county of Milwaukee and State of Wisconsin, have invented a new, original, and ornamental Design for a Doily or the like, of which the following is a specification, reference being had to the accompanying drawing, forming a part thereof.

The figure of the drawing is a face view of a doily or the like embodying my new design.

The design is an open work shown on a shaded background to better bring out the details thereof.

I claim:

The ornamental design for a doily or the like, substantially as shown and described.

KENNETH C. HAMILTON.
